HEAT ENGINE

William J. O'Leary, Dayton, Ohio

Application October 10, 1934, Serial No. 747,728
Renewed February 21, 1939

3 Claims. (Cl. 60—34)

The present invention relates to prime movers and more especially to heat engines.

The invention relates to constructions which improve engines of this type both in operation and in efficiency.

An object of this invention is to provide an atmospheric engine operating in part in response to atmospheric pressure applied to the open end of the piston.

Another object of this invention is to provide an engine that has a quick stroke in one direction and a slow stroke in the other.

Another object of this invention is to provide a valve mechanism that opens slowly and snaps into closed position.

Another object of this invention is to provide an engine having a quick stroke in one direction and a slow stroke in the other direction, that is provided with a valve mechanism having a slow stroke in one direction and a quick stroke in the other, said valve mechanism being timed to operate during one of the strokes of the piston.

With the above primary and other incidental objects in view, as will more fully appear in the specification, the invention consists of the features of construction, the parts and combinations thereof, and the mode of operation, or their equivalents, as hereinafter described and set forth in the claims.

In the drawings, Fig. 1 is an elevational view of the engine on the side of the valve with the flame director removed, and the fuel chamber in section. Fig. 2 is an elevational view of the opposite side of the engine with part of the cylinder in section. Figs. 3, 3a, 3b and 3c disclose a series of diagrammatic views illustrating various relative positions of the valve and piston. Fig. 4 is a detailed view illustrating the flame director in position. Fig. 5 is an arrangement of curves illustrating the relation between the slide valve travel and piston travel.

Fig. 6 is a diagram illustrating the operation of the piston in its relation to the crank connections. Fig. 7 is a sectional view taken on the line 7—7 in Fig. 1 of the slide valve which acts as a combined intake and exhaust valve.

Like parts are indicated by similar characters of reference throughout the several views.

Referring to the drawings and more especially to Figs. 1 and 2, the major portion of the engine comprises a frame casting 1, with which the cylinder block 2 and the fuel chamber 4 is an integral part. The forward portion is provided with pedestals 5 and 6 which carry the main shaft 7, and the pedestal 6 on the crank side is

strengthened by a web 8 which connects with a cylinder block 2. The cylinder 9 is bored out of the cylinder block 2 and is adapted to receive the piston 10 which is provided with a boss 11 that is connected with a pitman 12, which is attached to the crank disc 14 on the main shaft 7. A relatively heavy fly wheel 15 is mounted on the main shaft 7 between the pedestals 5 and 6. The slide bar 16 is bifurcated at 17 at its forward end to slide over and be guided by the main shaft 7 between the hub of the fly wheel 15 and the pedestal 6. The opposite end of this slide bar is provided with a slot 18 to slide over the stud screw 19 and carries a spring 20 which is perforated to form an opening through which the projection 21 on the slide valve 22 extends in order that the spring may hold the slide valve 22 against the slide face 24 through which the intake opening 25 leads into the cylinder 9. As shown in Fig. 7, the valve 22 is a D valve and it acts both as an intake valve and as an exhaust valve. When this valve is in its extreme right hand position (viewing the engine as in Fig. 1) it closes port 25 both to the atmosphere and to the flame. As the valve begins to move to the left, it first connects port 25 to exhaust passage 23 and then it opens the port to the flame. In this way, any pressure in the cylinder is exhausted directly to the atmosphere without blowing the flame away from the intake port 25.

The cylinder block 2 is provided at its upper portion with a water pan 26 adapted to contain water so that the temperature of the cylinder may be maintained within predetermined limits. An automatic pressure operated exhaust valve is provided adjacent the back cylinder wall and comprises an opening 27 leading into the cylinder, a valve seat chamber 28, a closure plug 46, having a threaded portion 29a. The valve is closed by a spherical member or ball 30. It is important that this valve member 30 shall be of a weight which will vibrate between the end of the valve closure and the valve seat at a rate which approximates the cycles of movement of the piston at the normal speed of the engine. The period may be varied by adjusting the distance between the valve seat and the valve closure, which adjustment may be effected by rotating member 46. If the valve member is heavy, it tends to cause the engine to run irregularly or may even stop. The same is true if the valve member is too light. I find that a ball of aluminum is best adapted for this work. It will be remembered that the slide valve 22 acts as

an exhaust valve and hence this ball valve is in some respects an auxiliary exhaust valve.

The forward end of the cylinder block is also provided with a receptacle 31 which may be filled with waste 32 so that oil on the waste will drip through the opening 34 to properly lubricate the cylinder walls and the piston. Preferably, this oil receptacle is closed by a closure plug 29.

The forward end of the slide bar 16 carries an anti-friction roll 35 which operates in a cam 36, preferably formed on the fly wheel 15. The major portion 37 of the cam 36 is circular and the minor portion 38 of the cam 36 is in the form of a chord subtending an arc of substantially 60° and terminating in an inner arc 37a connected to the major arc 37 by a radial portion 39. A spring 45 causes the valve 22 to snap into closed position when the roller 35 is aligned with the radial portion 39.

20 The frame 1 also carries as an integral portion a fuel chamber 4 from which a suitable burner head 40 is adapted to direct a flame upwardly adjacent the intake opening 25. This flame is directed toward the intake opening by a flame director 42 (see Fig. 4) so that as the engine is running in the direction of the arrow A, Fig. 1, the flame is sucked into the intake opening through the early part of the working cycle. The burner head 40 is set in a tube 43 which 25 extends into the fuel chamber 4 and prevents spilling the fuel when the engine is inverted or tipped over.

25 By referring to Figs. 2 and 6 it will be observed that a horizontal line through the axis of the main shaft 7 is considerably above a horizontal line comprising the axis of the bore of the cylinder 9. This arrangement produces a beneficial action which will be further discussed by reference to the diagram in Fig. 6.

30 40 By referring to Fig. 3c when the piston 10 is in the "in" position of the cylinder the longitudinal axis of the crank arm or pitman 12 intersects the axis of the crank shaft, which position will be referred to as zero position. The intake valve is now starting towards open position. When the crank shaft has rotated through an angle of 60° (as shown in Fig. 3) the intake valve is in extreme open position and the cam 36 ready at a slight additional movement to permit 35 the spring 35 to snap the valve into closed position, as shown in Fig. 3a. Referring now to Fig. 5, the abscissa represents equally spaced angular movements of the crank and the ordinate represents both valve opening and piston stroke. As a matter of convenience, the full valve opening and the piston stroke have been taken as having the same limit. It will be observed that the valve 22 begins to open substantially coincident with or slightly after zero position, and continues opening until slightly before the 60° point of movement of the crank and that it closes slightly before the crank has gone through 120°, with the cycle of movement of the valve comprising about 120° of crank angular movement. During the 45 time while the valve has been opened, the piston in moving toward the fly wheel has sucked in a portion of the flame from the burner head and has drawn in hot air together with gases or vapor produced by the action of the flame. This hot 50 air and gases are trapped in the closed cylinder when the valve 22 closes at about 90° of crank movement. From this point to the extreme travel of the piston which occurs when the crank is at about 170°, the gases and vapors in the cylinder 55 are reduced in pressure by the outward movement

of the piston. The expansion of the gas lowers the temperature of the fluids and vapors in the cylinder chamber. At the same time, the fluids and vapors are losing heat by absorption of the walls of the cylinder so that the vapors in the fluid commence to condense. This operation of the lowering temperature of the fluids and vapors in the cylinder produces a partial vacuum back of the piston which increases rapidly. The construction and arrangement of the operating parts 10 are so timed that the greatest reduction in pressure occurs slightly before the outward limit of travel of the piston. The momentum of the fly wheel carries the piston over this peak and enables atmospheric pressure to be immediately effective 15 on the return stroke so that the piston is returned with considerably more force than is required on the outer stroke. It is desirable that this force shall have time to exert itself fully 20 on the driving mechanism, and therefore, it is 25 particularly desirable that the outward stroke of the piston shall be relatively rapid and that the return stroke shall be relatively slow up until the latter portion of the stroke, when it is rapidly increased in speed. This action is obtained by 30 placing the axis of the crank shaft or main shaft in a horizontal plane considerably above the horizontal line of travel of the piston connection to the pitman, and this is most effectively accomplished by lowering the horizontal axis of the 35 piston so that it passes considerably beneath the axis of the main shaft 7. Referring to Fig. 6, it will be observed that starting with the zero position and considering equal angular movements around the crank shaft, (such angular movements being numbered 1, 2, 3, etc., and plotting corresponding positions for piston travel and numbering said positions 1a, 2a, 3a, etc.) that the movement of the piston in the stroke toward the fly wheel is considerably faster than its movement in the stroke away from the fly wheel. 40

45 It is seen from Fig. 6 that the piston is farthest from the fly wheel when the connecting rod is aligned with the radius of the crank, i. e., when the crank is in the position indicated as zero in Fig. 6. Similarly, it is seen that the piston is nearest the fly wheel when the connecting rod is superimposed upon the radius of the crank, which, as shown in Fig. 6, occurs when the crank is at about 155°. Accordingly, the stroke of the piston 50 from its farthest position from the fly wheel to its nearest position to the fly wheel is accomplished while the crank is rotating from zero to 155°, while the return stroke occupies the time it takes the crank to go from 155° back to zero, i. e., through an angle of 205°. The fly wheel is relatively heavy and hence the momentum causes it to have substantially the same angular velocity at all times. Accordingly, the piston speed in its movement away from the fly wheel is considerably 55 slower than its speed in its movement towards the fly wheel. The stroke away from the fly wheel is made while the fly wheel is rotating through only 155° while the return stroke over the same distance takes the time required for the fly wheel 60 to rotate through 205°.

65 During the return stroke, the speed of the piston is rapidly increased so that the residual vapors and gases are quickly compressed as the pressure in the cylinder changes from sub-atmosphere to super-atmosphere and these residual vapors and gases are therefore quickly expelled through the 70 exhaust valve 30. This valve 30 being light, it opens when the pressure in the cylinder is very little in excess of atmosphere so that there is very 75

little loss of power in this portion of the stroke since the front end of the cylinder 9 is at all times open and consequently, the forward face of the piston is always under full atmospheric pressure.

During operation of the engine the action of the D-valve and the exhaust port associated therewith is substantially as follows: Assuming the valve member to be in position completely closing the cylinder to the atmosphere and with the piston moving toward the closed end of the cylinder on the power stroke, the first movement of the valve member uncovers the exhaust port, permitting the exhaust of any remaining pressure within the cylinder. Further movement of the valve member uncovers the inlet port and as the piston moves away from the closed end of the cylinder flame is sucked into the cylinder. The valve member then closes quickly, covering first the intake port and then completely covering the exhaust port. A small amount of air may be sucked in through the exhaust port past the D-valve member, but the amount is so small as not to interfere appreciably with the working of the engine. Due to the cam arrangement with its chordal section, the opening of the valve member occurs gradually over a short period of time followed by a very sudden closing of the valve, so that the exhaust port is open to the atmosphere on both the exhaust and suction strokes for a very slight period.

The spring 45 causes the valve which has been gradually opened when the cam follower 35 moves along the fragmentary chord section 38, to snap into closed position when the cam follower enters the substantially radially arranged portion 39.

The closure plug 46, provided with a vent 50, is designed in the form of a whistle to emphasize the exhaust sounds to thereby simulate a large engine.

It is very important that the valve be closed rapidly at the right moment without gradually closing as the piston is now approaching its maximum speed.

From the above specified arrangement and construction, the efficiency of this type of engine is greatly improved and is raised to the point where the engine becomes sufficiently economical for practical purposes.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention is described in language more or less specific as to structural features, it is to be understood that the invention is not limited to the specific details shown, but that the means and construction herein disclosed comprise the preferred form of several modes of putting the in-

vention into effect, and the invention is therefore claimed in any of its forms or modifications within the legitimate and valid scope of the appended claims.

Having thus described my invention, I claim:

1. A flame engine operable on differential cylinder pressures comprising a cylinder having one end normally closed and the other end open to the atmosphere, a piston within said cylinder, an automatically operable exhaust valve, means to produce a flame adjacent the closed end of the cylinder, a chambered valve member operable to control admission of flame to the closed end of the cylinder and also supplementing the exhaust valve to exhaust residual gases therefrom through the chamber directly to the atmosphere and in a direction away from the flame, and means to mechanically actuate said valve member to effect said admission of flame during a portion of the piston stroke away from the closed end of the cylinder and to effect said exhaust prior to the next admission of flame.

2. A flame engine operable on differential cylinder pressures comprising means to produce a flame, a piston, a cylinder having one end open to the atmosphere and the other end normally closed, the closed end being provided with a port adjacent the flame and an exhaust passage leading into the open air away from said flame, a chambered slide valve member operable to connect said cylinder port with said exhaust passage through said valve chamber and then open the port to the flame, and means to mechanically actuate said valve member to open said port to said exhaust passage just prior to the time when the piston reaches dead center at the closed end of the cylinder.

3. A flame engine operable on differential cylinder pressures comprising a cylinder having one end normally closed and the other end open to the atmosphere, a piston within said cylinder, an automatically operable exhaust valve, means to produce a flame adjacent the closed end of the cylinder, a valve member operable to control admission of flame to the closed end of the cylinder and also supplementing the exhaust valve to exhaust residual gases therefrom directly to the atmosphere and in a direction away from the flame, and means to mechanically actuate said valve member to effect said admission of flame during a portion of the piston stroke away from the closed end of the cylinder and to effect said exhaust prior to the next admission of flame, said actuating means including a cam, a cam follower, said cam having a cam surface including a pair of straight portions interconnected by a pair of arcuate portions, one of said straight portions being tangentially disposed with respect to one of the arcuate portions for causing the cam follower to open the valve gradually and the other straight portion being radially disposed, and a spring for snapping the valve into closed position when the cam follower passes along the radially disposed portion of the cam surface.

WILLIAM J. O'LEARY.
